UNITED STATES PATENT OFFICE

2,448,340

ELECTRIC FLOOD SIGNAL

Jacob O. Williams, San Bernardino, Calif.

Application October 31, 1944, Serial No. 561,297

1 Claim. (Cl. 177—311)

1. This invention relates to flood signals and especially to signals giving warning that a dangerous condition has arisen near or behind a dam, levee, dike, canal, water breaker or the like, and it has for its object to provide an arrangement whereby a warning message is broadcast or special flood warning signals are actuated as soon as the situation has become critical.

The principal and most important component of the arrangement, according to the invention is a float operated switch, such as described in Patent No. 2,281,127, granted to me which closes electric circuits if the level raises above or falls below a high or low level mark respectively. This switch moreover, permits to cut out the use either of the high level or the use of the low level contacts in accordance with requirements, and the switch also permits testing of the equipment.

In the course of tests relating to the development of dangerous conditions, on, near, or behind a dam, like, levee, canal, or water breaker, it has been found that the known practice of giving an alarm signal to the operating personnel will lead to the timely operation of a public alarm only in cases in which dangerous conditions develop slowly or gradually. For, the starting of a public alarm cannot be entrusted to the persons directly receiving the alarm signals, who are not qualified to judge conditions. The notification that an alarming condition exists has therefore first to be transmitted to some responsible expert.

Quite a number of dangerous conditions, including those of the most dangerous type, arise moreover suddenly. Flooding due to cloud bursts, to heavy rain falls to the sudden melting of snow in great quantities or to a dam or dike break, may be mentioned as examples. Some defects leading to flooding may develop slowly, but the early stages are sometimes not discovered in time. Protection against such suddenly arising dangers is insufficient with the systems as above explained. To provide an alarm against suddenly occurring floods, it seems preferable to substitute a completely automatic public alarm for the alarm signals given merely to the operating personnel, as this substitution eliminates the risk of delays due to the fact that the personnel in such installations have to perform duties keeping them from the permanent watching of a signal. Such an automatic alarm device can however only be used if it is capable of discriminating between "normal" fluctuations, which do not produce alarming conditions, and conditions involving an imminent danger to life and property.

It is, therefore, one of the main objects of the

invention to arrange a float operated switch, such as described in my earlier patent, in such a relation to the dam, levee, dike, canal, or breakwater, that the water lever either sinks or raises to the point at which the float switch becomes operative merely in cases of great emergency. With this object in view the invention consists in a float operated switch, adjusted for operation at its low water level contacts which is located in a water chamber communicating with a channel or feedway the intake opening of which is located at a point which is only drained or depleted when abnormal or emergency conditions have developed.

Under these conditions the switch may form part of a control circuit directly controlling the operation of a wireless transmitter provided with a record modulating the carrier wave of the same which broadcasts an appropriate warning.

Where a public telephonic or telegraphic warning system is installed, it is clear that the switch may transmit its warning over this network.

The invention is illustrated in the accompanying drawings showing two modifications, one of which is relative to a system so arranged that the sinking of the water level below a certain mark will operate the alarm, while the other modification shows a system in which the raising of the water level above a certain mark will operate the alarm.

In the accompanying drawings

Figure 1 is a diagrammatic view of a dam site.

Figure 2 is a similar view of the same site taken at right angles to Figure 1.

Figure 3 is a diagrammatic view of a modification of the invention as used in connection with a dam or dike.

Figure 4 is a diagram of connections of the controlled alarm system.

As seen in the drawings, Figure 1 shows a dam site 5 indicating the top of a dam running across a valley.

The dam is provided with the customary overflow outlets 7, and with the additional outlets 8 and 9, the former being the outlet of an aqueduct, while the outlet 9, which is located below the low water level 16, is used for supplying a turbine.

Below this low water level a vaulted chamber 11 having the form of a vaulted passage is arranged communicating with a float chamber 12.

The location of chamber 11 has to be carefully chosen in accordance with conditions to be expected in connection with an expected emergency. In the event of a big dam the greatest danger is that due to a dam burst or break, causing the

valley below the dam to be flooded. When such a dam burst occurs, the water level suddenly drops, adopting an unusual position and inclination, which may be calculated in advance.

These water level demarcations, occurring in the event of a burst, break or washout followed by destruction of part of the structure, show a marked inclination towards the horizontal in the vicinity of the dam. They are represented in Figure 1 by the line 15, shown in dots and dashes. The water level near the dam leaves an approximately triangular zone below the natural level depleted of water as shown by line 15 and by selecting the place for the chamber 11 below the lowest natural level within this triangular zone, a sufficient degree of security is established so that the float chamber and the float will not be affected by conditions manifesting themselves during normal operation of the dam, but will cause the float to operate solely in the event of a dangerous break. It will be noted that emergency conditions which result in flooding are indicated by the depletion of the float chamber and by the operation of the low water level contacts of the switch, when the float has reached its lowest level.

Above the chamber 12, the float switch 18, described in Patent No. 2,281,127 is arranged. The push rod 10 mentioned in this patent and designated therein by the same numeral, and the float 17 are diagrammatically indicated in their position in chamber 12.

The float operated switch 18, which is mounted above chamber 12 is provided with contacts, of which only contacts 19, 20 need be mentioned. The former is the low level contact of the float switch, the latter the permanent circuit (Fig. 4) contact of the same. In the said circuit, which includes the battery or batteries 21, a relay 22, is arranged, controlling the current supply to the electronic equipment of the transmitter 23, and the motor 24 of the record carrier of a phonographic recorder 25. The transmitter by means of the antenna 26 is in a position to broadcast the recorded message.

Figure 3 shows an installation such as used in connection with a flood water resisting dam, dike or pier.

The dam, dike or pier is indicated at 30, the level of the earth or valley at 31. In the dam or pier a water intake 32 is arranged which forms the end of a water feedway or channel 33 communicating with the float chamber 34. In said chamber the float 17 and the float carrying push rod is arranged. Above it again the float switch 18 is mounted, connected with battery 21, relay 22, and circuit 23, as described before.

It will be noted that in this case the alarm system is connected with the high water level contacts of the float switch operated when the float has reached its uppermost or high level position.

A seepage water outlet 35 is arranged at an appropriate height to prevent water from underground sources to rise within the float chamber to a level which might cause operation of the float.

When water is rising to the level of the water intake, the feedway 33 and the chamber 34 is filling. When the chamber 34 is full of water the float is raised and operates the circuit in the manner already described.

It will be clear that the broadcasting system will be operated when the water has reached a dangerous level threatening to flood the valley protected by the dam or dike.

As mentioned, the signalling system and other details may be changed without departing from the essence of the invention.

What I claim is:

A discriminating protective public alarm system for supervising dikes and dams restraining a body of water, operated only under emergency conditions produced by a dam or dike break, but not operated by normal water level fluctuations, comprising a float chamber forming a separate closed compartment reaching down below the lowest low water level of the body of water, a float operated switch arrangement including a float operating within said float chamber and float controlled switch contacts operative at the lowest float level, a water channel, leading from said float chamber to the body of water and having its intake located below the lowest low water level immediately behind the dam or dike to be protected, within a triangular space uncovered solely upon formation of an inclined water level upon dam or dike break, and means, including an automatically operative broadcast transmitter, for transmitting an alarm message, operated by the said switch contacts.
